(57) CLAIM

The ornamental design for a clothing article with ornament, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front view of a clothing article with ornament showing our new design depicted on a clothing article shown in broken lines; and,

FIG. 2 is a front view of a clothing article with ornament depicting the ornament within broken lines showing environment.

The broken lines in FIGS. 1 and 2 form no part of the claimed design.

The claimed design consists of the solid lines and portions in between the solid lines.

1 Claim, 2 Drawing Sheets
(2 of 2 Drawing Sheet(s) Filed in Color)
